ELECTRICAL CONTACT

John B. Ford, Schenectady, N. Y., assignor to
General Electric Company, a corporation of
New York

Application February 1, 1935, Serial No. 4,483

3 Claims. (Cl. 200—166)

My invention relates to electrical contacts of the silver contact type and has for an object the provision of an inexpensive low resistance silver contact provided with a backing member which 5 may be readily united integrally with an iron or steel supporting member.

While silver has been commonly recognized as a good contact making and breaking material, its use has been restricted due to the difficulties 10 of securing the silver metal to steel supporting members. Heretofore the silver contacts have been formed as by coining or by the flowing of the silver metal under pressure into predetermined size, the pre-formed contact then being 15 applied to the supporting member either by riveting or brazing. While silver can be welded to iron or steel by exercising a great deal of care, welding is not practical for quantity production of switch members where the silver tips are welded 20 directly to the switch members due to the high percentage of rejects, i. e., switch members to which the silver contacts have not been welded securely. If the silver is secured to the switch member by brazing a flux must be used and the 25 temperature controlled very accurately. This method is too costly to be satisfactory. Riveting is unsatisfactory since additional operations are necessary and under the repeated stress of the opening and closing of the contacts the rivets 30 often are loosened sufficiently to interfere with the circuit making and breaking functions. It has been heretofore proposed to provide silver contacts with backing metals of copper or an alloy of copper and zinc, the backing metals 35 being used to decrease the cost of the contact and to afford a surface metal which can be secured to a supporting member by brazing or soldering. As I have said, however, brazing or 40 soldering operations are not desirable in quantity production due to the great care demanded to insure a minimum number of rejects.

In carrying out my invention in one form thereof I provide a pre-formed electrical contact having a body portion formed of silver and a backing member integrally united to the silver, the backing member being formed of steel. With such a pre-formed contact the steel member can be resistance welded to a supporting switch member of steel or the like without the 45 use of flux or other complicated manufacturing methods. I have found that by integrally uniting the steel backing member and the silver contact members prior to the mounting of the silver contacts to the switch members that the 50 pre-formed contacts can be resistance welded to

their supporting members by an automatic welding machine, the union between the steel supporting member and the steel backing member in all cases affording a strong and rigid connection. The result is that the life of the contacts is 5 lengthened, the resistance is decreased, and the cost of the preformed contact is decreased over a silver contact of corresponding size.

In order to assist in the positioning of the pre-formed contacts with reference to the switch member, the backing member is provided with one or more positioning projections which are arranged to nest within a centering groove provided in the switch member. Due to the thinning of the material in the switch member by the 15 groove and the relatively small cross sectional area of the projections, the maximum heat during the resistance welding is produced at the projections. During the welding these projections flow into the groove, the flowing of the metal 20 rapidly extending to the adjoining surfaces of the switch member and the backing member to provide an extremely strong union between the two.

For a more complete understanding of my 25 invention reference should now be had to the accompanying drawing wherein I have shown in Fig. 1 my invention applied to a switch member provided with a pair of silver contacts each having a backing member of steel; Fig. 2 is a perspective view of a pre-formed silver-steel contact and one end of the switch member shown in Fig. 1 prior to the union of the steel backing member with the switch member; Fig. 3 is a sectional elevation of the contact shown in Fig. 2; 30 while Fig. 4 illustrates a modified form of the invention.

Referring to the drawing, I have shown my invention in one form as applied to a steel switch member 10 provided with silver-steel contacts 11 40 and 12 of identical construction. The silver contact 11 consists of a body portion 13 formed of fine silver and a ferrous backing member 14 formed of free flowing steel composed mainly of iron. Preferably, the steel is heat treated for 45 maximum ductility, i. e., free flowing. The high ductility is desirable since it facilitates the preferred method of integrally uniting the silver to the steel by rolling together under pressure silver and steel bars which have been heated to 50 a predetermined temperature. After the relatively large bars have been thus integrally united and rolled to a predetermined thickness, composite members approximately the size of the contacts are stamped from the composite metal. 55

The finishing operation is performed by placing the composite members in dies and applying pressure of a magnitude sufficient to cause the metals to flow into the dies and form the finished contacts.

Instead of the hot rolling method, the bars or plates may be integrally united by other suitable methods well known to those skilled in the art such, for example, as by brazing.

10 The steel backing member 14 of the finished contact is provided with a plurality of frustroconical projections 15, each of which is located the same distance from the center of the backing member. These projections of gradually increasing cross-sectional area from their extremities to their base cooperate with a groove 16 formed in the end 17 of the switch member 10 and serve to position the contact 11 on the switch member preparatory to the welding operation. 15 The groove 16 shown as circular in form is complementary to the projections; that is to say, it is of substantially the same configuration so that its walls closely fit opposite sides of the projections and thereby insure accurate positioning of 20 the contact on the switch member.

Besides greatly facilitating the location of the contact on the switch member these projections perform an important part in the welding operation. For this operation, the switch member 10 25 is located in a jig of a resistance welding machine and the contact members 11 and 12 are placed in their respective grooves. The movable electrodes of the resistance welding machine are then brought to bear on the outer faces of the respective contact members to complete an electrical connection and to apply a predetermined pressure on the contacts. By reason of the groove 16 and the dimensioning of the projections 15 the welding current flowing from one electrode 40 to the other tends to concentrate through the path of lowest resistance provided by the projections 15 and the thinned portion of the switch member 10 at the bottom of the groove. The result is that the projections 15 are first melted, 45 the metal flowing along the groove and uniting with the melted walls of the groove. A strong

union of the steel backing member 14 to the switch member 10 is therefore in every case assured and I have found that faulty switch members have been practically eliminated because of improper welding of the parts. In fact, after the 5 steel backing member 14 has been welded to the switch member it is practically impossible to separate them.

As shown in Fig. 3, the thickness of the silver body portion 13 is preferably somewhat greater than the thickness of the backing member 14 although it is understood that the relative thicknesses can be varied as desired. Preferably, the backing member 14 is formed slightly concave so that the outer rim 14a overlaps somewhat the 15 face of the switch member 10. This construction is desirable because it reduces the thickness of the resulting switch member and contact assembly.

If desired, the silver body portion 13 can be 20 formed to overlap the outer edges of the backing member 14, this construction being shown in Fig. 4.

While I have shown a particular embodiment of my invention, it will be understood, of course, 25 that I do not wish to be limited thereto since many modifications may be made, and I, therefore, contemplate by the appended claims to cover any such modifications as fall within the true spirit and scope of my invention.

What I claim as new and desire to secure by Letters Patent of the United States, is:—

1. An electrical contact member comprising a body portion formed of silver and a backing member formed of a ferrous metal integrally se- 35 cured to said body portion.

2. An electrical contact member comprising a body portion formed of silver, a backing member for said body portion formed of steel, the adjoining surfaces of said body portion and said back- 40 ing member being integrally secured together.

3. An electrical contact comprising a body portion of silver and a backing plate formed of a free flowing metal composed mainly of iron integrally united with said body portion.

JOHN B. FORD.
